PRESSURIZED DISPENSING CONTAINER

Norman Usen, West Haverstraw, N.Y., assignor to Union
Carbide Corporation, New York, N.Y.

Filed Mar. 4, 1970, Ser. No. 21,745

Term of patent 14 years

Int. Cl. D9—01

U.S. Cl. D9—9

FIG. 1

FIG. 2

FIG. 3

FIG. 5

FIG. 4

FIG. 1 is a perspective view of a pressurized dispensing container showing my new design;

FIG. 2 is a side elevational view;

FIG. 3 is a front elevational view;

FIG. 4 is a top plan view; and

FIG. 5 is a rear elevational view thereof.

I claim:

The ornamental design for a pressurized dispensing container, as shown.
